UNITED STATES PATENT OFFICE

2,180,954

MACHINE FOR MAKING, FILLING, AND SEALING CONTAINERS

John K. M. Harrison, Ogontz, Pa.

Application October 11, 1937, Serial No. 168,345
Renewed February 17, 1939

54 Claims.

(Cl. 93—3)

This invention has general reference to machines for producing or making, filling and sealing containers air-tight continuously; while it relates more particularly to machines adapted for operation on preformed body shells of paper, fiber or analogous material; and is primarily directed to an amplification and continuation, in part, of certain common subject-matter included in my prior application for patent, Serial Number 69,805, filed March 20, 1936, and which later matured as Patent No. 2,106,739, dated February 1, 1938.

The main object of the present improvements is to provide a novel automatic machine for assembling, filling and sealing paper containers, from preformed body shell and end units, of predetermined size and capacity.

Another object is the provision of a machine of the indicated type, wherein the various cyclic procedures are operatively coordinated and interrelatedly effected in timed sequence.

A further object is the provision of a machine of the above specified character distinguished by a carrier means which is automatically returned to its lowermost, or normal, position in the event of exhaustion of any of the container forming components, jamming, speeding-up or retarding of the machine.

Other objects and advantages, more or less ancillary to the foregoing, and the manner in which they are realized in practice, will be hereinafter explained, or become apparent from a more complete examination of the following description, which, considered in conjunction with the accompanying sheets of illustrative drawings, set forth practical embodiments of the inventive features.

Generally stated, this invention embraces certain novel devices, combinations of means, and arrangements of parts hereinafter disclosed, illustrated by the drawings, and more concisely expressed in the claims at the conclusion of this specification.

In the drawings:

Fig. I, Sheet 1, is a side elevation, with a portion of the conveyor means removed to condense the view, of a typical form of the improved machine of this invention for making, filling and sealing, paper, fiber or analogous material containers.

Fig. II, Sheet 2, is a top plan view of the preceding Figure.

Fig. III, Sheet 3, is a similar illustration to Fig. I, but with parts broken out or removed to

better disclose underlying features of the invention.

Fig. IV, Sheet 4, is an end elevation looking towards the left hand of Fig. I, as indicated by the arrows IV—IV thereon.

Fig. V, Sheet 5, is a fragmentary plan view of that portion of the machine embraced between the arrows V—V, Figs. I and III, with the elevating table in the "down" position.

Fig. VI, Sheet 5, is a corresponding illustration to the preceding, but with the table in the "up" position.

Fig. VII, Sheet 6, is a plan view of the drive and heating means for the spinning heads, with parts broken away and in section to better disclose important features, and taken as indicated by the arrows VII—VII in Fig. III.

Fig. VIII, Sheet 7, is a part elevational and part sectional view, taken approximately on the plane marked VIII—VIII in Fig. I, of one of the 20 container end disc magazines, with the associated mechanism for moving a container body shell therebelow and releasing an end disc for partial insertion thereinto, and drawn to a larger scale for clarity of illustration.

Fig. IX, Sheet 8, is a corresponding illustration to the preceding, but with the parts in different relative position or after effecting insertion of an end disc into the container body shell.

Fig. X, Sheet 9, is an axial section illustrating 30 an intermediate position of the upper portion of Figs. VIII and IX, or when the container body shell is proximate to and under the "capping" head ready to receive and have inserted therein and end closure or disc.

Fig. XI, Sheet 9, is a detail plan view, taken approximately as indicated by the arrows XI—XI in Fig. VIII.

Fig. XII, Sheet 9, is a view similar to the preceding, but taken on the plane XII—XII of Fig. X.

Fig. XIII, Sheet 9, is a similar plan view, on the plane XIII—XIII of Fig. IX.

Fig. XIV, Sheet 9, is a vertical section on the plane XIV—XIV of Fig. X.

Fig. XV, Sheet 9, is a similar section on the plane XV—XV of Fig. X.

Fig. XVI, Sheet 6, is a horizontal section on the plane XVI—XVI in Fig. III, but drawn to a larger scale, and illustrating in detail a "scraper" mechanism, hereinafter fully explained, in its inactive position.

Fig. XVII, Sheet 6, is a similar view to the preceding, but showing the "scraper" mechanism in the active position.

Fig. XVIII, Sheet 10, is a fragmentary plan view of a turn-over mechanism effective to invert the container subsequent to having the initial or bottom end closure or disc fully inserted therein and the beading operation performed.

Fig. XIX, Sheet 10, is an elevation of the same, as viewed in the direction of the arrows XIX—XIX, Fig. XVIII.

Fig. XX, Sheet 10, is a vertical section, looking in the direction of the arrows XX of Fig. XVIII.

Fig. XXI, Sheet 11, is a detail plan view of a punching mechanism, hereinafter fully set forth, for producing a pressure venting orifice in the container body shells prior to filling and closure.

Fig. XXII, Sheet 11, is a broken, larger scale, elevation of the means shown in the preceding view, with the punching means in the inactive position.

Fig. XXIII, Sheet 11, is a similar view, with parts in vertical section, but showing the punching means in the active position.

Fig. XXIV, Sheet 11, is a detail section on the plane XXIV—XXIV of Fig. XXIII.

Fig. XXV, Sheet 11, is a vertical section as viewed in the direction of the arrows XXV—XXV of Fig. XXII.

Fig. XXVI, Sheet 12, is a detail plan view with parts in section, of the container filling-valve and associated control mechanism, taken approximately on the plane XXVI—XXVI of Fig. III.

Fig. XXVII, Sheet 12, is an elevation of the preceding view on the plane indicated by the arrows XXVII—XXVII thereon, with the filler valve closed.

Fig. XXVIII, Sheet 12, is a similar elevation to the preceding, but also including the cam actuator means and with the filler valve open for discharge of a predetermined quantity of substance or liquid into the container.

Fig. XXIX, Sheet 12, is a fragmentary detail of the filler valve actuator means.

Fig. XXX, Sheet 13, is a plan view on the plane XXX—XXX of Fig. III, and showing the cooperatively related mechanism whereby the several movements and interrelated actions involved in the machine of this invention are accurately timed.

Fig. XXXI, Sheet 13, is a broken detail viewed in the direction of the arrows XXXI—XXXI of the preceding figure, or the cam means controlling the container progressing and end inverting mechanism.

Fig. XXXII, Sheet 13, is a similar view on the plane XXXII—XXXII of Fig. XXX, and illustrative of the cam effective to control the return conveyor motion.

Fig. XXXIII, Sheet 13, is a like view as indicated by the arrows XXXIII of Fig. XXX, showing the table raising and lowering cam means.

Fig. XXXIV, Sheet 13, is a vertical section on the plane XXXIV—XXXIV of Fig. XXX, showing the raising and lowering cam means for both conveyors and a small-elevating table herein-after specifically described.

Fig. XXXV, Sheet 13, is a similar section on the plane XXXV—XXXV of Fig. XXX, of a filling valve and punch actuating cam mechanism.

Fig. XXXVI, Sheet 2, is a detail plan view of a transfer device operative to move the inverted containers from the forward conveyor to the return conveyor for filling and closing, or discharge at that end of the machine to which the container body shells are supplied.

Fig. XXXVII, Sheet 2, is an elevation looking from below the preceding view.

Fig. XXXVIII, Sheet 2, is a view corresponding to Fig. XXXVI with the transfer device in the inoperative or neutral position.

Fig. XXXIX, Sheet 2, is an elevation viewed from below Fig. XXXVIII.

Fig. XL, Sheet 14, is a sectional view depicting the mode of chamfering the peripheral edges of a container body-shell prior to applying an end disc or closure thereto.

Fig. XLI, Sheet 14, is a similar view, showing an end closure in position ready for insertion into the body shell.

Fig. XLII, Sheet 14, illustrates the succeeding step of forcing the end closure into the body shell with incidental slight expansion of said shell end.

Fig. XLIII, Sheet 14, shows the concluding operation of beading over the expanded shell end into reinforcing contact with the end closure outer surface.

Fig. XLIV, Sheet 15, is a plan view along the lines of Fig. II, showing a modified form of the invention.

Fig. XLV, Sheet 15, is a cross section on the plane XLV—XLV of Fig. XLIV, but drawn to a larger scale.

Fig. XLVI, Sheet 15, is a perspective view of a turnover member involved in the mechanism of Fig. XLV.

Fig. XLVII, Sheet 16, is a wiring diagram showing how the container elevating table of the machine is automatically returned to its normal or lowermost position when the supply of end closures becomes exhausted or in the event the speed of the machine advances or slows down unexpectedly; or the automatic action of said machine should be otherwise adversely affected; and,

Fig. XLVIII is a wiring diagram of the several heater heads.

Referring more in detail to the drawings, it will be seen the improved machine of this invention comprises a suitable base 1 to which is anchored spaced side members 2 rigidly braced by cross-ties 3. Intermediate the side members 2 is a stationary bed 4 including a vertically movable section or main table 5, the purpose whereof will be later on fully set forth. The bed 4 and table 5 are longitudinally grooved at 6, 7, respectively, for the reception of reciprocative and vertically movable conveyor elements or bars 8, 9, having spaced upwardly-directed projections 10, 11, those on the one bar 8 being active in one direction or toward the left-hand, for example, and those on the other bar 9 active in a reverse or right-hand direction.

The conveyor bars 8, 9, are reciprocative in notched guides 12 disposed across the stationary bed 4, and said bars are arranged for intermittent timed actuation through the medium of rocker elements 13, pivoted at 14 between the bed side flanges 15. These rocker elements 13 have camming projections 16 for coaction with the lower edges of the bars 8, 9, and said elements are operatively coordinated by connecting-rods 17, influenced in one direction by retractile springs 18 and movable in the other in opposition to said springs by pivotal arms 19, fulcrumed at 20. These pivotal arms 19 carry rollers 21 engaging projections 22 on the connecting rods 17, as well as rollers 23 coactive with cams 24 on a rotary cam-shaft 25 transversely journaled between the side members 2 aforesaid. Now it will be readily seen on reference to Figs. III and XXXIV, more

particularly, that as the cams 24 are revolved in the direction of the arrow on the latter figure, the pivotal arms 19 will be intermittently swung in a clockwise direction by the cams 24 with resultant movement of the rocker elements 13 on their pivots 14 in a reverse or anti-clockwise direction, whereby the conveyor bars 8, 9 will automatically recede into the grooves 6, 7, and vice versa as said bars are influenced by the springs 18. Track or guide rails 26 parallel each of the conveyor bars 8, 9, and serve to guide thermoplastically-lined container body shells 27 into and part way through the machine; and subsequently similarly progress for filling and closing containers 28 to discharge from said machine. As the body shells 27 are consecutively entered into the machine, each one is firstly advanced onto the table 5, by which it is elevated into registration and engagement with a rotary heater head 29, at station A, adapted to soften the thermoplastic lining 30 and also chamfer the shell free upper edge at 31 as shown in Fig. XL. The means for intermittently elevating the table 5 preferably comprise links 32 pivoted at 33 below the guides 12, and also articulated at 34 to arms 35 carried by transverse shafts 36 intermediate brackets 37 extending downwardly from the side flanges 15 of the machine bed 4. Fixed to the shaft 36 are arms 35*, in turn coupled together by a link 38 for operation in unison by means of a connecting-rod 39, having its one end fulcrumed thereto at 40 and the other longitudinally slotted at 41, Fig. XXXIII, with a laterally-projecting roller 42 for coaction with a sectoral cam 43 fixed on the shaft 25, and rotative in the direction of the arrow on said cam to effect reciprocation of the connecting-rod 39 and elevation of the table 5, as hereafter more fully set forth.

In order to ensure accurate centering of each container body shell 27 relative to the rotary heater head 29, as well as other instrumentalities operating thereon during advancement along the table 5, the latter is provided with upstanding stationary guide elements 44, 45, and relatively movable grip members in the form of arcual-section plates 46. These grip plates 46 are supported by stems 47, slideable in a vertically movable bearing 48, and have short links 49 fulcrumed to their free ends, said links in turn being operatively connected at 50 to arms 51, fast on rock-shafts 52. These rock-shafts 52 are journaled in spaced bearings 53 of suitable guide brackets 54, 54' attached to, or formed integral with, the elevating table 5, hereinbefore referred to. Means such as slotted cams 55 secured to the rock-shafts 52, and engaging freely rotative rollers 56 at the outer ends of lateral projections 57, of the stationary bed side flanges 15, serve to project the arcual grip plates 46 inwardly and outwardly when the table 5 is raised and lowered, as clearly understandable on reference to Figs. VIII and IX, more particularly. In connection with the means just described, and for a purpose hereinafter set forth, there is provided what may be termed a latch-cam 58, pivoted at 59 to the vertically movable table 5, with its one end or tail 60 under the influence of a retractile spring 61, while the other or camming end 62 is outwardly angled relative to an intermediate stop portion 63, the purpose of which is later on explained, and said camming end 62 is provided with a vertically-directed extension 64. This extension 64 is disposed in the path of, and adapted for coaction with, a lateral projection or stop 65 of a latch tongue or member 66, pivoted at 67 to

the base 68 of a vertically movable head 69 and inserted longitudinally-slotted tube 70 adapted for seating reception of a removable magazine 70*, of end closures as well as a housing 71 for the end closure applying head 72 which is arranged to partially insert a cap or end closure 73 into the body shell 27 therebelow. The applying head 72 is enclosed in the housing or casing 71 which has a tubular portion 74, in which the stem 75 of said head is axially movable, with its upper portion in a stationary guide structure 76; and between the guide structure 76 and the top of the housing 71 is a spring 77 in compression, said spring being guided by axially aligned stop rods 78, 79. The lower end of the latch tongue 66 is cut out or shouldered at 80 for engagement with an intermediate bar portion 54* of the guide bracket 54 to effect simultaneous elevation of the movable head base 68 with that of the table 5 as later on set forth.

Supported by the vertically-movable head 69 with capacity for intermittent reciprocation is an ejector device or slide 81, see Figs. X-XV more particularly, having one end conformatively curved at 82 for circumferential engagement with the individual end closures 73 as they are ejected from the removable magazine seating tube 70, by the means now to be described. This means comprises a pair of links 83, coupled at 84 to the ejector slide 81, and at 85 to the lower ends of angle members 86, fulcrumed at 87 to the tubular portion 74 of the movable head 69. Journaled between the upper and laterally projecting parts 88 of the members or levers 86 is a roller 89 co-active with an undulate strap-like cam 90 integral with, or secured to, the applying head stem 75, as best shown in Fig. X. This strap-like cam 90 embodies an active portion 91 and a dwell part 92, while the housing tubular portion 74 of the movable head 69 is vertically slotted at 93, for passage therethrough of said cam, as well as to accommodate its up-and-down movement.

When a body shell 27 is moved into position below the movable head 69 at station B with an end closure 73 thereover, all the parts just described being in the position of Fig. VIII, the table 5 and with it said body shell commence to rise, the latch cam 58 having located the tongue 66 in the path of the upward travel of an integrally-formed bar portion 54* of the guide brackets 54 or 54', until it comes in contact with the guide bracket 54 and elevates the magazine base 68 with it. The roller 89, Fig. VIII, then rides over the cam 91 causing the slide 81 to move, toward the left-hand through action of the links 83, to the position shown in Figs. IX and XIII, at which time a fresh end closure 73 drops in front of the active or curved end 82 of the slide 81. When the end closure 73 is initially placed in the body shell 27, the table 5 and magazine parts 70, 70* and 71 commence to descend, the roller 89 following vertically until it strikes the lower horizontal portion of the strap-like cam 90, whereupon further descent of the parts 70, 70* and 71 causes the roller 89 to move outwardly and upwardly over the active part 91 of said cam, and thereby effecting transfer of the released end closure 73 aforesaid, between the spring clips 96 into position over the tapering aperture 94; see Figs. VIII and XI.

This tapering aperture 94 serves for passage of the container body shell 27 upwardly into the housing 71 and partial insertion thereinto of a cap piece or end closure 73; while it is to be observed from Figs. X-XIII the aperture 94 is

surroundingly recessed at 95 and fitted with the opposing inwardly acting spring clips 96, referred to above, said clips serving to grip the circumferential edge of the end closure 73 and prevent its dropping through the aperture 94 until the body shell 27 moves upwardly into concentric relation therewith. Incidentally, it is to be also remarked the latch tongues 66 are integrally or otherwise connected by a cross-tie 97 so as to 10 positively ensure their movement in unison, as well as to prevent accidental disalignment, or binding of the end applying head stem 75 in the tubular portion 74 of its housing 71, and incidental distortion of the tube body shell 27.

15 In conjunction with the slotted tube 70 there is provided a detector device 98, see Figs. VIII, IX and XV, more particularly, operative to direct attention to the fact when said slotted-tube 70 needs replenishing with end closures 73, as well 20 as in circuit with mercoid-switches 99, 99', Figs. I, IV and XLVII in circuit with the main switch 100, for a purpose later on explained. The detector device 98 is preferably in the form of a counterweight lever with one arm 102 longer than 25 the other 103, and a relatively offset angularly-directed branch 104. This branch 104 serves, when in the vertical position of Figs. IV and XV, to engage and trip the mercoid-switches 99, 99' in advance of the main switch 100 controlling 30 the motor 101, as later on further amplified; while the detector device 98 is pivoted at 105 to a lug 106 projecting laterally from the movable head 69. The detector device 98 normally occupies the position shown in Fig. I, that is to 35 say with the branch 104 inclined over from the vertical, or until the arm 103 is moved inwardly over the exhausting end closures 73, as shown in Fig. XV, whereupon the branch 104 becomes vertically-directed and aligned for coaction with the 40 mercoid-switches 99, 99', as hereinafter more fully explained.

When either magazine 70* is loaded with end closures 73, the detector device 98 is retained, in the position shown in Fig. I, by contact of the arm 45 103 with the edge of said closures, in an obvious manner. The branch 104 is inclined to allow the arm of the mercoid switch 99, or 99', to ride between it and the other arm 103 on elevation of the table 5. Now it will be clearly apparent that, as 50 the magazine 70* becomes partially exhausted, see Fig. XV, the detector device 98 swings on its pivot 105, under the influence of its longer arm 102, whereby the shorter arm 103 is projected inwards over the end closures 73, thus swinging the 55 angularly-directed arm 104 into vertically-directed and aligned position for coaction with the mercoid switch 99, or 99'.

The container body shell 27 with the partially-inserted end closure 73 is now lowered by the 60 table 5 away from the end applying or "capper" head 72 and progressed by the conveyor 8 into axial registration below the rotary "spinning" head 107, at station C whereupon the table 5 is again elevated by the means hereinbefore described. The body shell 27 and end closure 73 being raised into the spinning head 107, which is heated and preferably of the type disclosed in my prior patent, No. 2,106,739, dated February 1, 1938, and as it is pushed into said head, turns 65 over and inwardly heads the contacting shell end, while forcing the end closure into its final sealed position.

The container 28 thus formed is now complete with respect to its bottom, and is lowered away 70 from the "spinning" head 107 and transferred to

the next station "D" where it is again elevated by the table 5, and by means of appropriate mechanism stamped or printed with the desired designating matter. This mechanism conveniently comprises bell-crank members 108, at 5 each side of the machine, pivoted at 109 to proximate vertical standards 110, upstanding from the stationary bed 4, said members each having one arm forked at 111 for operative coaction with lateral studs 112 projecting from the adjacent table bearing 48. The other or upper arm of each crank member 108 is pivoted at 113 to an associated connecting link 114, in turn fulcrumed at 115 to the outer end or stud portion 116 of a rectangular-section stepped-member 117. Each 10 stepped-member 117 is guided for horizontal movement by passage through a slot 118, Fig. V, in a lateral projection or arm 119, of the associated standard 110, and a reciprocatory rod 120 15 slidable in apertured lugs 121 integral with said 20 arm and standard. Vertical movement of the table 5 will thus be seen effects reciprocation of each stepped-member 117, and by aid of an appropriate applicator roll 122 at the inner end 25 thereof transfers suitable marking medium from 30 a pad 123 to the lower face of each stamping device 124 concurrent with the ascending movements of the table 5, ready for marking the exterior end surface of the containers 28, as successively elevated into contact therewith. 35

The stamped container 28 on being lowered by descent of the table 5 is moved by the conveyor 8 into registration with a turn-over mechanism, Figs. I, III, and XVIII-XX. This turn-over mechanism preferably comprises a bracket 125 35 extending upwardly from one of the machine side flanges 15, said bracket serving for rigid support of a bearing element 126 on which is freely journaled a sleeve 127, having at one end a gear 128 in mesh with a reciprocative toothed rack-bar 40 129, sustained by a freely-rotative roller 130, in turn supported by the bracket 125. Secured to the sleeve 127, at its inner end, as by a set-screw 131 is an abutment collar 132 intermediate which, and a slidable sleeve 133 on said sleeve 127 is a 45 spring 134 under compression. The slidable sleeve 133 is maintained against rotation, relative to the sleeve 127, by a key 135, while the outer end of the sleeve 133 engages with the inclined or cam face 136 of the vertically-slotted 50 portion 137 of a bracket means 138 integral with vertically-movable table bearing 54. Integral with the collar 132 and the slidable-sleeve 133 are arms 139, 140. Now as the table 5 elevates, as shown in Fig. XIX, the arm 140, carried by the 55 slidable sleeve 133, Fig. XVIII, will move inwardly toward the arm 139, under the action of the cam face 136, carried by the table 5, compressing the spring 134 and clamping the container 28. The rack bar 129 is then advanced towards the 60 right in Fig. XIX under action of the cam 152, Fig. III, through the roller 151, lever 148, rod 147, and arm 143, rotating the pinion gear 128 in counterclockwise direction, thus inverting the container 28. The table 5 is then lowered, causing release of the container 28, by separation of the clamp arms 139, 140 by cooperation of the cam face 136 and the spring 134. Further rotation of the eccentric cam 152 restores the clamp arms 139, 140 to their normal position, see Fig. 65 I, in readiness to receive the following container 28. The rack 129, as best understood from Figs. I and III, is fulcrumed at 141 to one arm 142 of a special link, the other arm 143 whereof is parallel thereto and both of said arms are piv- 70 75

oted at 144 to an intervening upright 145 fixed to, or integral with, the side member flanges 15, and said arms 142, 143 are rigidly united by a strap piece 146. The lower end of the arm 143 is coupled by a connecting rod 147 to the upper end of a rock lever embodying upper and lower relatively-angled sections 148, 149, having a pivot stud 150 at the angular part, with a roller 151 engaging on, and operated by, the eccentric cam 152, above referred to, on the main drive shaft 25 of the machine, while the lower linkage component 149 is coupled at 154 to the stationary fulcrum 20, transversely between the machine side members 2. A second connecting rod 156 intervenes the upper end pivot 157 of the knee-action linkage 148, 149, and a downward lug 158, Fig. XXXI, below the conveyor bar 8, while a recoil spring 159, Fig. I, serves to maintain the roller 151 always in contact with the cam 152, 20 in an obvious manner.

The inverted container 28 is next moved by the conveyor bar 8 into a position for further elevation by a second narrow table *t* and action thereon by a punching mechanism, best shown in Figs. XXI-XXV, inclusive, and functional to produce a small vent hole, or holes, 160 through said container side wall near its top.

Referring now to Figs. III and XXXIV, the narrow table *t* is elevated and lowered by the cam 24, employed also to raise and lower the conveyor bars 8 and 9, as previously explained. Also carried by the connecting-rod 17 is an actuator cam 263; and extending downwardly from beneath the center of the table *t*, Figs. III and XXX, is a shaft 264 guided for free movement by a bracket 265, formed integral with one of the cross-ties 3. A roller 266, carried by the shaft 264, cooperates with the cam 263, thus raising and lowering the table *t* as the connecting rod 40 17 is reciprocated.

The punching mechanism comprises a dependent rigid bracket 161 having a horizontally-disposed and bored head separated by a suitable cut-out 162 into two axially aligned cylindrical portions 163 and 164. The horizontal portion 164 houses a peripherally flanged die 165 and an abutment member 166 having an axially disposed punch 167 passing through the bore of said die, with a spring 168, Fig. XXIII, normally tending to force the die 165 outwards. Vertically of the horizontal portion 164 is a guide member 169 having a cushioning spring 170 about its stem between the head 171 thereof and a bridging ejector 172 with lateral arms 173 adapted to engage the top edge of the container 28. The ejector 172 it will be observed best from Fig. XXIV embodies a central inverted channel-portion of a width between the lateral arms 173 to permit free movement up-and-down of the container 28 by coaction with side grooves 174, provided for the purpose in the horizontal portion 164, while it is to be noted the lower end of the guide member 169 is screw-threaded at 175 into the portion 164 for the sake of rigidity; while the abutment member 166 is secured against movement when adjusted by a set-screw 176, in an obvious manner. Reciprocative in the cylindrical portion 163, aforesaid, is a matrix 177 having a bore 178 for coaction with the punch 167, and a discharge duct 179 connecting with an outlet chute 180, for the punchings. After punching the vent hole 160 in the container side wall, there is a likelihood of the container sticking 75 between the matrix 177 and the flanged die 165

upon lowering of the table 5, due to the thermoplastic lining of the container.

The ejector 172, upon lowering of the table 5, will maintain the container seated upon the table, forcing the container from between the matrix 177 and the flanged die 165 under the influence of the spring 170. The matrix 177 is operatively coordinated with a slide bar 181, by a fork 182, and it has an elongated slot 183 whereby it is reciprocative by a tooth-cam 184 engaging a roller 185 projecting laterally from said slide bar, while the cam 184 is fixed on a rotary shaft 186 journaled in the machine side members, hereinbefore referred to, said shaft passing through the bar slot 183, to accommodate reciprocation of the bar 181, in an obvious manner. Means such as a spring 187 anchored between a lateral pin 188 on the bar 181, Fig. XXI, and the shaft 186 maintain the roller 185 in constant engagement with the tooth-cam 184.

The punched container 28 next passes to a switch device, by successive movements, for shifting its position sidewise to the return conveyor 9. This switch device, as indicated in Figs. I-III, and to a larger scale in Figs. XXXVI-XXXIX, comprises a vertically mounted pivot 189 having a sleeve or collar 190 secured thereto, above the plane of the stationary bed 4, said collar embodying a suitably-contoured transfer arm 191, functional to effect movement of the containers 28 from the conveyor 8 to the reversely active conveyor 9, and an angularly-related actuator arm 192 whereby the pivot 189 is turned to the left, for example, as later on explained.

To the lower end of the pivot 189 is fixed a second collar 193 with an arm 194 operatively connected by a twist-link 195 to the connecting-rod 17, hereinbefore referred to, with capacity for relative sliding movement through the medium of a slot 196 in said link engaging a lateral stud 197 on the connecting rod 198 of the proximate rocker element 13, each of said rocker elements being similarly connected to the connecting rod 17.

In order to effect turning movement to the left-hand of the transfer arm 191, the adjacent end of the conveyor bar 8 is formed to U-shape, as indicated at 199, and provided with a pin 200 in the path of the actuator arm 192. By rotation of the cam 24 in the direction of the arrow, Fig. XXXIV, the rod 17 is moved toward the left, lowering the conveyor bar 8

through movement of the rocker elements 13, and placing the pin 200 in the path of the actuator arm 192; while movement of said rod 17 also causes the stud 197 to slide in the slot 196 of the twist link 195 from right to left as shown in Figs. XXXVI-XXXVII. By further rotation of the shaft 25 carrying the eccentric cam 152, Fig. XXXI, the conveyor bar 8 moves toward the left, Figs. XXXVI-XXXVII, and the pin 200 coming in contact with the actuator arm 192 shifts the latter from the full-line position to the dot-and-dash line position, thereby transferring the container 28 from the conveyor 8 to the return conveyor 9 and places the parts in the position shown in Fig. III. Upon further rotation of the eccentric cam 152, Fig. XXXI, the conveyor bar 8 U-shaped end 199 carrying the pin 200 is moved toward the left or to its extreme position passing by the free end of the actuator arm 192.

In reverse order the rod 17 is first shifted toward the right, elevating the conveyor 8 through the rocker elements 13 and placing the pin 200 above the level of the actuator arm 192. At the same time the stud 197 returns the transfer arm 70

75

70

75

70

75

70

181 to its initial position, by coaction of the stud 187 with the slot 186 in the twist bar 185 under pull of the spring 18. The conveyor bar 8 having been elevated above the stationary bed 4 is 5 returned or moved toward the right in Fig. 5 XXXIX by the spring 159 with the pin 200 riding above the actuator arm 192 and at the same time moving another container 27 into the path of the transfer arm 191. Thus it will be readily 10 understood that as the switch device is moved from the full line position of Fig. XXXVI to the dot-and-dash position indicated thereon, the container 28 engaged by the transfer arm 191 will be laterally-shifted from further progression 15 by the conveyor bar 8 into a position for reverse progression by the conveyor bar 9.

The conveyor bar 9 is actuated by means similar to that explained in connection with Fig. XXXI, and accordingly like reference characters 20 are applied to Fig. XXXII with an added "prime" exponent in order to obviate unnecessary repetitive description. It is, however, to be observed the conveyor bar projections 11 are reversely active relative to the projections 10 on 25 the bar 8; while the cam 152' is set at 180° relative to the shaft 25 so as to be alternatingly effective in respect to the cam 152.

The conveyor bar 9 now intermittently advances the container 28 into position below the filling mechanism which comprises a suitable receptacle or tank 201 of the substance with which said container is to be filled, said tank being suitably supported above the machine bed 4 by the side member 2. Referring now, more 30 particularly to Figs. I, III, and XXVI-XXIX, inclusive, it will be seen the tank 201 has an axial funnel-shaped base 202 with an outlet 203 into a control valve 204 and associated measuring-ejector device 205. The plug 206 of the valve 204 has fixed to its lower end a plate 207 having a relatively eccentric pivot 208 to which is fulcrumed the one end of an actuator connection 209, whose remote end is rectangularly-apertured at 210 for reception of a slide block 211, in turn pivotally supported by an arm 212 fixed to the rotary shaft 186, hereinbefore mentioned. The rectangular aperture 210 is provided with a relatively inclined notching 213 which is adapted to intermittently hold the block 211 arrested, as indicated in Fig. XXVIII. The shaft 186 is partially turned at regular intervals, through the medium of an arm 214, at an angle to the arm 212, and a vertically-reciprocative bar 215, slotted at 216 for passage of the main drive shaft 25, said bar supporting freely-rotative rollers 217, 218 respectively coactive above and below a somewhat pear-shaped rotary cam 219 fast on the main drive shaft 25. Referring back again to the measuring-ejector device 205, which is 50 substantially of known type with a plunger rod 220 extending outwardly therefrom, said rod is provided with a rack portion 221, meshed by a toothed sector 222 fast on a transverse shaft 223, journaled in the upper parts of the side members 2, hereinbefore mentioned. This shaft 223 is alternately turned in both rotative directions through the medium of a link 224 and pitman 225 fulcrumed to a variably-adjustable axis block 226 slidable in an arcual slotted-guide 55 rail 227, by aid of a manipulator-screw 228 and hand-wheel 229. The guide 227 in turn has an extension 230 providing a pivot connection for the upper end of a second pitman 231 and at its lower end is similarly fulcrumed to a crank 232.

75 Associated with the control valve 204 is a

planarly-angled trip-lever 233 pivoted at its angular point to a laterally-extending axis pin or stud 234, projecting from the frame structure 2, said lever having one end looped at 235 for engagement upon the top edge of each rising 5 container 28, as it is elevated for filling by the control valve 204. This trip lever 233 has its remote portion 236 disposed in the plane of the descending actuator connection 209, and it is under the influence of a spring 237 tending to 10 always elevate the portion 236 and thus normally hold the lever 233 in the position shown in Figs. XXVI, XXVII and XXIX; while the connection 209 is under the influence of a retractile spring 238, Fig. XXVI, anchored between pins 239 and 15 240, respectively, on the frame structure 2 and said connection. From the immediately preceding description it will be readily apparent that when the actuator connection 209 occupies the full line position of Figs. XXVI and XXVII, the 20 control valve plug 206 is in a position to permit flow from the tank 201 via its outlet 203 and an elbow passage 241 in said plug, or oil for example in the tank 201 to the measuring-ejector device 205, and that on movement of the actuator connection 209 to the right-hand as viewed in 25 said figures, the plate 207 will be turned to the dot-and-dash position of Fig. XXVI, and the plug correspondingly moved to shut-off communication between the tank 201 and the measuring-ejector device 205. Incident to actuation of the valve plug 206 as just described, and inward movement of the plunger rod 220 by counter-clockwise turning of the toothed sector 222, the 30 measure content of the device 205 will be ejected 35 via the elbow passage 242 in the plug, from said device 205 into the container 28 elevated by the table t into registration with the control valve 204. If for any reason whatsoever a container 28 should fail to get beneath the looped end 235 of the trip lever 233 as the table t rises, the portion 236 of the lever 233 will support the actuator connection 209 keeping the block 211 at the bottom of the slot 210 and upon further clockwise movement of the arm 212 the block will pass by 40 the notch 213, Fig. XXIX, allowing the valve 206 to remain closed.

The tank is preferably supplied automatically from any convenient source of oil, or other medium, with which the containers 28 are to be 50 filled by way of a feed pipe 243 and conventional float control 244, whereby a constant level is maintained in said tank and pressure variation of the feed into the containers 28 is avoided.

The filled container 28 is next lowered and transferred by the conveyor bar 9 into registration with a heater-chamfering means at the station designated A', Figs. V and VI, corresponding with the rotary heating-chamfering head 29 hereinbefore described; thence to a closure applying head similar to 72, at station designated B'; beading-over and fully inserting head like 60 107 at station designated C'; and printing means at the station D'; all of said means corresponding with the several related mechanisms previously 65 described and differentiated only by prime exponents insofar as visible parts are concerned to avoid undue repetitive description. The guide rails 26 are provided along the stationary bed 4 to each side of the vertically movable table 5 in 70 order to prevent lateral displacement of the body shells 27 and containers 28 incidental to their progression through the machine. After leaving the station D' the filled and closed containers 28 are removed from the machine, at the same 75

end as the preformed body shells 27 enter, by any appropriate mechanism, not shown, for subsequent "proofing" treatment against the ravages of exposure to different atmospheric conditions, 5 if deemed necessary.

In order to concurrently operate the several heater-chamfering heads 29 and 29', at stations A—A', as well as the end fully-inserting and "spinning" heads 107 and 107' at stations C—C', 10 use is made of the vertical motor 245, Figs. I—III more particularly, mounted on an appropriate platform 246. The shaft 247 of the motor 245, which is preferably electric, extends downwards and is fitted with a pinion 248 in mesh with speed 15 reducing gears 249, 249', respectively, fast on the spindles 250, 250', Fig. VII, of the "spinning" heads 107, 107'. Below the respective gears 249, 249' and fast on the spindles 250, 250', are sprockets 251, 251' coordinated by chain drives 20 252, 252' to speed-reducing gears 253, 253' on the spindles of the heater-chamfering heads 29, 29', whereby the latter are simultaneously rotated with the "spinning" heads 107, 107'. Brushes 254, 254' are provided for electrically heating 25 the respective heads 29, 29' and 107, 107' in accordance with known practice.

Pivottally mounted in a slot 255 in each of the heater-chamfering head matrices 29'', or stationary components thereof, by means of a stud 30 256 is an inwardly active scraper 257 under the action of a spring 258 intermediate the tail 259, of said scraper, and a suitable anchorage 260 on the adjacent vertical standard 110. These scrapers 257 conform with and normally engage 35 the circumferential surface and chamfering portion 31 of the heater chamfering heads 29, 29' as indicated in Figs. XVII and XL, but are moved away therefrom by inclined cam devices 261, Figs. I, IV, XVI and XVII, carried by the vertically-movable table 5, as the latter elevates, and as clearly understandable from Fig. XVI: while 40 each scraper 257 embodies a chute 262 for conducting away the thermoplastic removed from said heads, after each body shell 27 has been chamfered and lowered away from the associated head 29 or 29', in a manner well understandable without further explanation herein. Referring back again to the main switch 100, and as best shown in Fig. IV, it will be seen the same is 45 provided with an on-and-off arm 153 carrying a roller 153' for engagement by an upstanding member 155 from the movable bearing 48'. As the table 5 is elevated, the arm 153 carrying the roller 153' is permitted to rise from the full line 50 position to the dot-and-dash line position, following the upstanding member 155 and thus closing the general circuit of Fig. XLVII; whereas upon lowering of said table 5 the arm 153 of the main switch 100 will through the upstanding member 55 155 reopen the circuit, such action continuing alternately so long as the machine is operating normally.

In addition to the switches 99, 99' and 100 aforesaid, the machine is provided with a push-button manual control switch 270 the "on" button being designated 271, and the "off" button marked 60 272; the purposes whereof will be more fully explained in connection with the wiring diagram of Fig. XLVII; while 273, 273' indicate pilot-lights in connection with the wiring scheme of Fig. XLVIII for the various heater and spinning heads, as later on fully disclosed, or when the current of their controlling circuit is "on" and the motor 245 in 65 operation.

75 Referring now to Fig. XLIV, which illustrates

a slightly modified form of the invention, or a machine of the straightaway type wherein the body shells 27x are, for example, fed in at the right-hand end thereof, while the filled and sealed containers 28x are discharged at the other or 5 left-hand end of said machine; or vice versa. Furthermore in this form of the invention two or duplicate conveyor bars 8x are operative in parallelism whereby duplicate body shells 27x and containers 28x are concurrently operated on, 10 so that the capacity of the machine is doubled; while use of a transfer device such as is described in connection with the parts 189—200 of the hereinbefore described machine, is rendered totally unnecessary. The various means performing the 15 successive operations are all more or less similar to those described in connection with Fig. II more particularly, accordingly corresponding reference characters are employed with a differentiating x prime in order to obviate as far as possible 20 repetitive description. Briefly, however, it is to be noted the preformed body shells 27x are fed to the stationary bed 4x, in pairs and spacedly related for intermittent advancement by the conveyor bars 8x, and between the guide rails 26x 25 until they reach the station designated Ax where they have their upper peripheral edges chamfered by heater heads 29x, as hereinbefore described. From the station Ax the body shells 27x are 30 successively advanced to the stations marked Bx, Cx and Dx, whereat they are respectively supplied with end closures 133x, beaded over, and stamped by means 69x, 101x and 124x, all as readily understandable from the description of the lower half of Fig. V and traveling in the 35 direction indicated by the arrow thereon, or from right to left.

Continued progression of the now bottomed containers 28x next brings them into the region of the turn-over mechanism, which for convenience is comprehensively designated 125x—140x. This turn-over mechanism differs somewhat from the form previously described in connection with Figs. II—III and XVIII—XIX, in that the bearing 126x, sleeve 127x, and slidable sleeve 45 133x are lengthened as shown in Figs. XLV and XLVI. More specifically the slidable sleeve 133x is formed with two tubular portions 267 and 268, rigidly connected together by an intervening bridge portion 269 so that they are operable in unison. Two abutment collars 132x, duplicate springs 134x are also employed in this form of turn-over mechanism in order to operate the necessary pairs of arms 139x, 140x of said mechanism at the station E, E, Fig. XLIV. The containers 28x are next advanced to the punching station F, F whereat, as hereinbefore set forth in connection with Figs. XXI—XXV they are provided with vent holes 160x, not shown, in readiness for progression into registration with the 50 filler control valves 204x, and measuring-ejector devices 205x shown at the station designated G, G. A tank similar to that shown at 201 in Figs. II and III is mounted on the side members 2x, 2x for supply of the desired medium, oil for 55 example, to the devices 205x and valves 204x, such as shown by Figs. XXVI—XXIX. The filled containers 28x are now ready for closure and sealing, and they are accordingly intermittently advanced by the conveyor bars 8x, 8x into registration with heating-chamfering heads 29x at station H, thence to the end closure partially-inserting the heads 69x at station I, on to the "spinning" heads 107x at the station J, and finally to the stamping devices 124x at the station 70 75

K; from which latter station the closed and sealed containers 28x are progressed intermittently to discharge at the left-hand end of the machine. Elevating tables 5x similar to the tables 5 shown in Fig. III, and correspondingly operated, are used in this form of the machine; as well as tables tx corresponding with the tables t are employed respectively at the stations Ax—Dx, H—K, and stations F, G. In all other respects this form of 10 the invention substantially conforms with the disclosure in Figs. I—XLIII, accordingly further amplification is deemed unnecessary.

Referring now to Figs. XLVII and XLVIII the former of which may be generally termed the "machine-circuit" and the latter an auxiliary or "heater control circuit", it is to be noted in connection with the former figure that the numerals 213x indicate supply and return wires; 214 a knife switch with associated fuses 215, for 20 example, connecting by cross-over wires 216 to line wires 217 including suitable fuses 218, serving to prevent damage to the machine in the event of "overloading", or other adverse operating mishap, said fuses and line wires being 25 mainly enclosed in a suitable fuse box or cabinet 219. The line wires 217 from one side of the cabinet 219 connect with the vertical motor 245 through the medium of a conventional knife switch 280; while the line wires from the other 30 side of the cabinet 219 connect through a knife switch 281 and magnetic controller 282 to the machine operating motor 101. From one of the line wires 217' a cross-over wire 283 connects with one terminal of the manual control switch 35 270 whereas a second wire 284 from another or the outer one of the wires 217' connects into the coil 285 of the magnetic controller 282. A branch wire 286 from the other end of the coil 285 connects to one terminal of the mercoid switch 99', for example, and thence through a return wire 287 to the other mercoid and manual-control switches 99 and 270 respectively, in an 40 obvious manner. In a like manner current is taken from one of the wires 217', to the wire 283, to one side of the table control switch 100, thence through the wire 284, and coil 285, to the outer wire 217', thence through the knife switch 281, wire 217, fuse 218, wire 216, fuse 215, knife switch 274 to the return wire 273.

50 Referring now to Fig. XLVIII, supply wires 288 with a return 288' furnish current through a knife switch 289 with associated fuses 290. Connecting with one of the outer fuses 290 is a lead wire 291 connecting with one terminal of a conventional thermostat 292, and from the other terminal whereof a wire 293 connects with the heating element 294 of the rotary head 29, for example, with return by way of a wire 295 to one terminal of an ammeter 296; while a pilot 55 light 273 is arranged in parallel relation to the wires 291 and 295. A second thermostat 298 has a branch 299 from the wire 291 and a wire 300 connects through the heater element 301 of the end spinning head 69, with a lead 302 to the wire 295. Reversely a wire 303 connects from the other outer fuse 290 through a branched-in thermostat 304 to the heater element 305 of the heating head 29' on the reverse side of the machine; while a return wire 306 connects through 60 the ammeter 296' and fuse 290' to the return wire 288' of the source of supply. A continuation of wire 303 connects to the one terminal of a second thermostat 307, and from the other terminal, of said thermostat, through a wire 308 65 to the heater element 309 of the spinning head

69'; whereas a return wire 310 leads from the element 309 through the ammeter 296', and fuse 290' to the main return wire 288', as before described. The pilot light 273' is arranged in parallel between the wires 303 and 310 as before set 5 forth. At this juncture it may be well to remark that the thermostats 292 and 304 control the amount of heat given to the chamfering heads 29, 29', respectively, and maintain the same at approximately 600° F.; whereas the 10 thermostats 298 and 307 similarly control the heater elements 301 and 309, of the end inserting and beading-over or spinning heads 107 at around 350° F.; while the pilot lights 273, 273', serve to indicate when the current for operating 15 the heads aforesaid is "on" or "off".

Assuming now that the knife switches 214, 280, 281 and 289 are all inserted to furnish electric current from sources of supply 213x and 288; the filling tank 201 properly replenished with oil, 20 or other desired fluent or semi-fluent; the magazines 10* charged with end closures 13, and the table 5 in its lowered position, with the mercoid switches 99—99' and the main control switch 100 all closed, with a few body shells in position 25 at the entering end of the machine, see Fig. I, the operator thereupon pushes in the "on" button 271 of the manual control switch 270. Incident to "pushing-in" of the "on" button 271, it will be readily seen that the main motor 101 is 30 set in operation; while previous closure of the knife switch 280 has similarly set in operation the motor 245, by closure of the knife switch 289, and which effects closure of the several circuits involved in the heating system of Fig. 35 XLVIII.

Now it will be evident that as the thermoplastically lined body shells 27 are intermittently advanced by the conveyor bars 8 and initially raised by the vertically movable table 5 they will be 40 consecutively chamfered at station A, Figs. III—V and VI, around the upper edge 31 and concurrently have the thermoplastic lining 30 locally softened. The treated shell 27 is next lowered by the descending table 5 and moved 45 by the conveyor 8 into a position for axial reception of an end closure 13 from the adjoining magazine 10* at station B and partial insertion into said body shell by re-elevation of the table 5 and coaction therewith of the applying head 50 12, as hereinbefore disclosed. The body shell 27 with the inserted end closure or bottom to be 55 13 is again lowered by the table 5, and progressed by the conveyor 8 into registration with the "spinning" head 107 at station C, and upon 60 re-elevation of the body shell 27 has its edge beaded-over into sealing engagement with the bottom 13. The table 5 is again lowered and the inverted container 28 is advanced by the conveyor 8 into registration with the stamping device 124 at station D, whereupon the table 5 is again raised and the container 28 appropriately marked by said device.

Upon re-descent of the table 5 and stamped 65 container 28, the latter is progressed by the conveyor 8 into the operative zone of the turn-over mechanism 125—140, Figs. VIII—Xx, whereupon it is automatically picked up by the arms 139, 140, swung over so that its open end is uppermost, and is re-engaged by the conveyor 8, and 70 advanced onto the narrow table t, by which it is elevated into coaction with the punching means 161—176, Figs. XXI—XXV, for production of the vent-hole or holes 160, as hereinbefore set forth. The punched container 28 is 75

next intermittently progressed by the conveyor 8 to the switch means, Figs. II, XXXVI-XXXIX more particularly, for lateral shifting to the return conveyor 9 by which it is progressed in a reverse direction into registration with the filling means 201-242, Figs. III and XXVI-XXIX more particularly, and upon elevation by the table 5 said container is filled with the requisite amount of material it is desired, in this instance 10 oil for example.

Upon descent of the table 5, the filled container 28 is moved and raised to the second heating-chamfering head 29, at station A', see Figs. V and VI; whereupon said container is 15 again lowered and moved by the conveyor 9 into registration with the applying head 72, at station B', for partial insertion of the top closure 73 as previously described in connection with the bottom; and incidentally it is to be remarked 20 this insertion is only permitted to partially cover the vent hole 160, Fig. XXIII, so that the contained compressed air can escape, as well as any air heated by the container or its content.

The filled container 28 is now lowered again 25 and advanced by the conveyor 9 and raised to the "spinning head" 107', at station C', which forces the top closure 73 home or past the vent hole 160, so as to seal said hole and evacuate, as far as possible, all superfluous air above the top of the 30 content of the filled container 28; as well as bead over the peripheral end edge of said container into mutual engagement with the container wall and the closure 73 outer peripheral surface. If it were not for the fact the closure 73 is held in 35 place by the beaded over edge, the still partially softened thermoplastic might permit said closure to rise, but the entrained pressure produced by the closure 73 moving partly below the vent hole 160 is automatically relieved when said entrained pressure cools down to the normal temperature 40 of the container 28 with resultant production of a permanent sealing-on of the top closure 73. The filled and sealed container 28 is now lowered away from the spinning head 107', advanced again by 45 the conveyor 9 and raised to the registration with the stamping device 124', at station D', and then further progressed by the conveyor 9 to discharge, at the entering end of the machine, for removal for packing, or further exterior air proofing if deemed desirable or expedient.

From the foregoing, the operation of the modified form of the machine, illustrated and explained in connection with Figs. XLIV-XLVI, will need no explanation herein, other than it involves plural straight-away conveyors whereby the output is doubled, and no return or switching means is included.

Furthermore, it may be remarked that in the event of one of the magazines 70* becoming exhausted of closures or cups 73, on the upward movement of the table 5 the detector arms 98, 98' will trip the mercoid switches 99 or 99' to open position, but the motor 101 will continue to further elevate the table 5, the circuit being held closed by the main control switch 100. As the table 5 descends, the switch control finger or up-standing member 155 comes into contact with the switch roller 153', moving the latter down from the dot-and-dash line position of Fig. IV, 60 to the full line showing therein and thereby shutting-off the motor 101 as the table 5 approaches its lowermost position, so that it automatically seats itself without any reactive influence incidental to fading-out momentum, and stoppage of 65 the motor 101. Obviously, when the machine is

"shut down", the switches 274 and 289 are opened.

Finally, while the principles of this invention may be carried out in various ways, and by the use of different means, the embodiments shown 5 are particularly advantageous, since they are mechanically simple both as to their construction and actuation. Also for the purposes of illustration, there is shown and described forms of the invention of the most practical kind, the 10 same are submitted for illustrative purposes only, and that extensive deviations may be made therefrom without departing from the spirit and scope of the invention as defined in the following 15 claims or the prior art proscribes.

Having thus described my invention, I claim:

1. In a machine for treating preformed container body-shells, filling and sealing the same, the combination of a shell receiving and intermittently-progressing mechanism; means for feeding end closure elements to the body shells; a main and an auxiliary elevators interposed in the path of, and coactive with, the progressing mechanism; individual devices for simultaneously heating and chamfering the body-shell 25 ends, other devices for applying and sealing bottom and top end closures to the body-shell with an intervening device for filling the containers; mechanism coordinatively actuating all of said devices in timed relation; and means for automatically stopping the machine in the event of any obstructive tendency arising.

2. In a machine for treating preformed container body-shells, filling and sealing the same, the combination of a shell receiving and intermittently-progressing mechanism; means for feeding end closure elements to the body shells; a main and an auxiliary elevators interposed in the path of, and coactive with, the progressing mechanism; sequentially-related individual devices for simultaneously heating and chamfering the body-shell ends, other devices for applying and sealing bottom and top end closures to the body-shell under definitely controlled heat, intervening marking devices and filling devices for 40 the consecutive containers, for subsequent progression to discharge; mechanism for coordinatively operating all of said devices in timed relation; and means for automatically stopping the machine in the event of any obstructive tendency 50

3. A machine as defined in claim 1, wherein the main and auxiliary elevators are spacedly related, and an intervening coordinatively-operated turn-over mechanism moves the bottomed 55 body-shell from off the main elevator and deposits it on the auxiliary elevator open-end up- 55 permost.

4. A machine as defined in claim 1, wherein the main and auxiliary elevators are spacedly 60 related, a coordinatively-operated turn-over mechanism intervenes said elevators so that the bottomed body-shell is moved from off the main elevator and deposited on the auxiliary elevator open-end uppermost, and punching means co- 65 ordinatively actuate with the ascent and descent of the auxiliary elevator, whereby one or more vent holes are made through the container wall near its upper open-end.

5. A machine as defined in claim 1, wherein the intermittent-progressing means comprises forward and return sections, and switch means intervenes said sections whereby the consecutive 70 bottomed and marked containers are moved from 75

the forward section to the return section, for filling and closure.

6. A machine as defined in claim 1, wherein the progressing means are arranged in parallel so that plural body shells may be simultaneously acted upon, and coordinatively-operative and sequentially-related multiple devices serve for heating and simultaneously chamfering said body-shell ends, other devices apply and seal bottom and top closures, and intervening devices fill the bottomed body shells.

7. A machine as defined in claim 2, wherein the progressing means are arranged in parallel so that plural body shells may be simultaneously acted upon, and mechanism coordinatively-operates sequentially-related multiple devices for simultaneously heating and chamfering said body-shell ends, other devices for applying and sealing-in bottom and top closures, intervening devices for filling the bottomed body shells, as well as further devices for respectively turning-over the bottomed body shells and for forming vent orifices near the open ends thereof.

8. A machine as defined in claim 2, wherein the various means and devices are all electrically actuated, with inclusion in the machine operating circuit, of a manual control switch, mercoid switches automatically operate upon approaching exhaustion of the end closure elements, and a normally-closed main elevator ascent and descent control switch, also serves in conjunction with the mercoid switches to shut-off the actuating means in the event of any tendency to "overload", or otherwise adversely affect automatic running of the machine.

9. In a machine for converting thermoplastically-lined preformed body shells into filled and sealed containers, the combination of means for simultaneously heating and chamfering the shell ends, means for feeding bottom and top closure elements to said ends, means for partially inserting said closure elements into the shell body, means for further forcing the said closure elements into the body shell to form surrounding impervious joints and concurrently seal the container projecting end portions into beaded union with the closure elements and the adjoining body shell.

10. In a machine for converting thermoplastically-lined preformed body-shells into filled and sealed containers, the combination of means for heating and chamfering one end of the body shell, means for feeding and locating a preformed bottom concentric with the body shell heated end, means for partially inserting said bottom into the body shell, heated rotary means for further forcing the bottom inwards to form an interior impervious joint and concurrently spin the shell projecting peripheral portion into lapping relation therewith, means for filling the container thus formed, means for similarly treating and applying a top to the container to effect its sealed closure, and mechanism whereby all of the foregoing means are all coordinatively-operated in sequentially timed-relation.

11. In a machine for converting thermoplastically-lined preformed body-shells into filled and sealed containers, the combination of means for heating and chamfering one end of the body shell, means for feeding and locating a preformed bottom concentric with the body shell heated end, means for partially inserting said bottom into the body shell, heated rotary means for further forcing the bottom inwards to form an interior impervious joint and concurrently

spin the shell projecting peripheral portion into lapping relation therewith, means for filling the container thus formed, means for similarly treating and applying a top to the container to effect its sealed closure, means for venting air pressure from within the filled container incidental to the top applying and sealing operation, and mechanism whereby all of the foregoing means are all coordinatively-operated in sequentially timed-relation.

12. In a machine for converting thermoplastically-lined preformed body-shells into filled and sealed containers, the combination of means for heating and chamfering one end of the body shell, means for feeding and locating a preformed bottom concentric with the body shell heated end, means for partially inserting said bottom into the body shell, heated rotary means for further forcing the bottom inwards to form an interior impervious joint and concurrently spin the shell projecting peripheral portion into lapping relation therewith, means for filling the container thus formed, means for similarly treating and applying a top to the container to effect its sealed closure, means for venting air pressure from within the filled container incidental to the top applying and sealing operation, means for impressing on the exposed faces of the bottom and top closure elements appropriate marking characteristics of the container content, and mechanism whereby all of the foregoing means are all coordinatively-operated in sequentially timed-relation.

13. In a machine for converting preformed paper body shells having a thermoplastic lining into filled and sealed containers, the combination of rotary means for partially heating and inwardly-beveling one end edge of the body-shell container-forming unit, means for feeding a suitable material bottom into registration with the heated body-shell end and partially inserting same therewith, means for fully forcing said bottom under applied heat into the container body to form an impervious juncture with the shell interior lining and to concurrently spin the projecting end of the shell wall into lapping engagement with said bottom, means for similarly treating and applying a top to the container to effect sealed closure thereof, electrically-actuated mechanism whereby all of the preceding means are coordinatively-operated in timed sequential relation, and fuse means for automatically stopping the machine in the event of "overloading" or other adverse operating mishap.

14. In a machine for converting a preformed paper body-shell having an interior coating of a suitable thermoplastic into a filled and sealed container, the combination of means for partially heating and peripherally flaring one end of said shell; means for moving a fibrous disc bottom, having an inner facing and circumferential edge flange of fusible sheet material, into axial registration with the shell heated end and partially inserting same therewith with concurrent uniform expansion of the body-shell heated end; rotary spinner means with associated heater means for further forcing the disc bottom into the body-shell to the requisite extent for formation of a surrounding fused fillet-like impervious-juncture between the interior coating and the bottom facing, said spinner means also serving to bead the body-shell outer projecting edge into lapping engagement with the bottom circumferential edge facing flange; means to support the open end of the container during the

bottom fitting and spinning operations, said means also operating to elevate the container; means for formation of a vent in the body-shell wall near its open end; means for filling the container; means for applying a correspondingly faced disc top to the container after filling; means for treatment of the container upper projecting edge as aforesaid for sealed closure thereof; and means coordinatively effecting all of the foregoing operations in timed sequential relation.

15. In a machine for converting a preformed paper body-shell having an interior coating of a suitable thermoplastic into a filled and sealed container, the combination of means for partially heating and peripherally flaring one end of said shell; means for moving a fibrous disc bottom, having an inner facing and circumferential edge flange of fusible sheet material, into axial registration with the shell heated end and partially inserting same thereinto with concurrent uniform expansion of the body-shell heated end; rotary spinner means with associated heater means for further forcing the disc bottom into the body-shell to the requisite extent for formation of a surrounding fused fillet-like impervious juncture between the interior coating and the disc bottom facing, said spinner means also serving to bead the body-shell outer projecting edge into lapping engagement with the bottom circumferential facing flange; means to support the open end of the container during the bottom fitting and spinning operations, said means also operating to elevate the container; means for formation of a vent in the body-shell wall near its open end; means for filling the container; means for applying a correspondingly faced disc top to the container after filling; means to effect sealed closure between the disc top and said surrounding container edge while simultaneously freeing air pressure from within the filled container by way of the vent aforesaid; and means for effecting all of the foregoing operations in coordinatively timed sequential relation.

16. In a machine for producing, filling and sealing containers, the combination of means for receiving and intermittently progressing preformed suitably-lined body shells; main elevating means for initially raising the body shells individually into coaction with a combined heating and edge-chamfering head and lowering the shell away therefrom; guide and grip means on the main elevating means for accurately centering the body shells and containers relative to said head and other instrumentalities successively operating thereon; said progressing means next advancing the body shell along the elevating means into and away from a bottom closure partially-inserting head; magazine means for feeding and sustaining closure elements above the body shells in readiness for insertion with associated actuator latch cams; a bottom closure fully-inserting and edge-spinning head; an appropriate marking device; said progressing and main elevating means jointly further moving the body shell into and away from the bottom closure fully-inserting and edge-spinning head, as well as into registration with the marking device, and withdrawing the same therefrom; a relatively-spaced smaller elevating means; said progressing means next advancing the now bottomed and marked container from the main elevating means to an inverting mechanism whereby the container open end is turned uppermost and said container again deposited on the smaller elevating means, punching means for producing a vent or vents proximate the top of the open container and mechanism whereby the smaller elevating means raises said container into coaction with said punching means and lowers the same therefrom; means for automatically forcing the vented containers away from the punching means after actuation of the latter; a switch means whereby the punched container is next moved to a return conveyor; a filler means into registration with which the container is raised and lowered by the smaller elevating means aforesaid for subsequent passage onto the main elevating means and intermittently progressed, raised and lowered into coactive relation with another heating and edge-chamfering head, a top closure inserting and edge-spinning head, and an end marking head, all as aforesaid; means controlling the degree of heat supplied to the respective heads requiring the same; means whereby the main and auxiliary elevating means are automatically returned to their lowermost position in the event the end closures are nearing exhaustion; mechanism coordinating all of the preceding means for operation in timed relation; and means whereby the machine is automatically stopped in the event of any unforeseen eventuality.

17. A machine as defined in claim 16, for producing, filling and sealing containers, wherein the means for directing attention to the fact when the supply of closure elements is nearing exhaustion, consists of a detector device operative to give a visible signal; and means whereby the machine is automatically stopped through action of said device in the event of any unforeseen eventuality.

18. A machine as defined in claim 16, wherein the receiving-progressing means comprises parallel advance-and-return conveyor bars respectively having reversely-active projections, and means for timed actuation of said bars.

19. A machine as defined in claim 16, wherein the receiving-progressing means comprises parallel advance-and-return conveyor bars respectively having reversely-active projections, pivotally mounted rocker elements having cam portions engageable below the associated conveyor bars, a connecting rod operatively coordinating all of the rocker elements, retractile means influencing said rod in one direction, a pivotal arm with a roller at one end engaging a projection on the connecting-rod in opposition to the retractile means, and a second roller on the pivotal arm coactive with a sectoral cam on the main rotary shaft of the machine, whereby the conveyor bars are intermittently actuated.

20. A machine as defined in claim 16 wherein the main elevating means comprises a table extending across the machine stationary bed, and means for intermittently raising and lowering said table relative to the planar surface of the bed.

21. A machine as defined in claim 16 wherein the main elevating means comprises a table extending across the machine stationary bed, said table and bed having longitudinal grooves for reception of the receiving-progressing means, links pivoted below the table and articulated to arms on transverse shafts intermediate the machine sides, other arms depending from said shafts and coupled together by a link for operation in unison, a connecting rod having one end fulcrumed to one of the depending arms with its other end longitudinally-slotted for passage of the machine main drive shaft, said latter end supporting projecting rollers, and a segmental

mate the top of the open container and mechanism whereby the smaller elevating means raises said container into coaction with said punching means and lowers the same therefrom; means for automatically forcing the vented containers away from the punching means after actuation of the latter; a switch means whereby the punched container is next moved to a return conveyor; a filler means into registration with which the container is raised and lowered by the smaller elevating means aforesaid for subsequent passage onto the main elevating means and intermittently progressed, raised and lowered into coactive relation with another heating and edge-chamfering head, a top closure inserting and edge-spinning head, and an end marking head, all as aforesaid; means controlling the degree of heat supplied to the respective heads requiring the same; means whereby the main and auxiliary elevating means are automatically returned to their lowermost position in the event the end closures are nearing exhaustion; mechanism coordinating all of the preceding means for operation in timed relation; and means whereby the machine is automatically stopped in the event of any unforeseen eventuality.

15. In a machine for converting a preformed paper body-shell having an interior coating of a suitable thermoplastic into a filled and sealed container, the combination of means for partially heating and peripherally flaring one end of said shell; means for moving a fibrous disc bottom, having an inner facing and circumferential edge flange of fusible sheet material, into axial registration with the shell heated end and partially inserting same thereinto with concurrent uniform expansion of the body-shell heated end; rotary spinner means with associated heater means for further forcing the disc bottom into the body-shell to the requisite extent for formation of a surrounding fused fillet-like impervious juncture between the interior coating and the disc bottom facing, said spinner means also serving to bead the body-shell outer projecting edge into lapping engagement with the bottom circumferential facing flange; means to support the open end of the container during the bottom fitting and spinning operations, said means also operating to elevate the container; means for formation of a vent in the body-shell wall near its open end; means for filling the container; means for applying a correspondingly faced disc top to the container after filling; means to effect sealed closure between the disc top and said surrounding container edge while simultaneously freeing air pressure from within the filled container by way of the vent aforesaid; and means for effecting all of the foregoing operations in coordinatively timed sequential relation.

16. In a machine for producing, filling and sealing containers, the combination of means for receiving and intermittently progressing preformed suitably-lined body shells; main elevating means for initially raising the body shells individually into coaction with a combined heating and edge-chamfering head and lowering the shell away therefrom; guide and grip means on the main elevating means for accurately centering the body shells and containers relative to said head and other instrumentalities successively operating thereon; said progressing means next advancing the body shell along the elevating means into and away from a bottom closure partially-inserting head; magazine means for feeding and sustaining closure elements above the body shells in readiness for insertion with associated actuator latch cams; a bottom closure fully-inserting and edge-spinning head; an appropriate marking device; said progressing and main elevating means jointly further moving the body shell into and away from the bottom closure fully-inserting and edge-spinning head, as well as into registration with the marking device, and withdrawing the same therefrom; a relatively-spaced smaller elevating means; said progressing means next advancing the now bottomed and marked container from the main elevating means to an inverting mechanism whereby the container open end is turned uppermost and said container again deposited on the smaller elevating means, punching means for producing a vent or vents proximate the top of the open container and mechanism whereby the smaller elevating means raises said container into coaction with said punching means and lowers the same therefrom; means for automatically forcing the vented containers away from the punching means after actuation of the latter; a switch means whereby the punched container is next moved to a return conveyor; a filler means into registration with which the container is raised and lowered by the smaller elevating means aforesaid for subsequent passage onto the main elevating means and intermittently progressed, raised and lowered into coactive relation with another heating and edge-chamfering head, a top closure inserting and edge-spinning head, and an end marking head, all as aforesaid; means controlling the degree of heat supplied to the respective heads requiring the same; means whereby the main and auxiliary elevating means are automatically returned to their lowermost position in the event the end closures are nearing exhaustion; mechanism coordinating all of the preceding means for operation in timed relation; and means whereby the machine is automatically stopped in the event of any unforeseen eventuality.

17. A machine as defined in claim 16, for producing, filling and sealing containers, wherein the means for directing attention to the fact when the supply of closure elements is nearing exhaustion, consists of a detector device operative to give a visible signal; and means whereby the machine is automatically stopped through action of said device in the event of any unforeseen eventuality.

18. A machine as defined in claim 16, wherein the receiving-progressing means comprises parallel advance-and-return conveyor bars respectively having reversely-active projections, and means for timed actuation of said bars.

19. A machine as defined in claim 16, wherein the receiving-progressing means comprises parallel advance-and-return conveyor bars respectively having reversely-active projections, pivotally mounted rocker elements having cam portions engageable below the associated conveyor bars, a connecting rod operatively coordinating all of the rocker elements, retractile means influencing said rod in one direction, a pivotal arm with a roller at one end engaging a projection on the connecting-rod in opposition to the retractile means, and a second roller on the pivotal arm coactive with a sectoral cam on the main rotary shaft of the machine, whereby the conveyor bars are intermittently actuated.

20. A machine as defined in claim 16 wherein the main elevating means comprises a table extending across the machine stationary bed, and means for intermittently raising and lowering said table relative to the planar surface of the bed.

21. A machine as defined in claim 16 wherein the main elevating means comprises a table extending across the machine stationary bed, said table and bed having longitudinal grooves for reception of the receiving-progressing means, links pivoted below the table and articulated to arms on transverse shafts intermediate the machine sides, other arms depending from said shafts and coupled together by a link for operation in unison, a connecting rod having one end fulcrumed to one of the depending arms with its other end longitudinally-slotted for passage of the machine main drive shaft, said latter end supporting projecting rollers, and a segmental

cam on the main drive shaft of the machine jointly cooperative with said projecting rollers to effect intermittent raising and lowering of the table.

5 22. A machine as defined in claim 16 wherein the guide and grip means for accurately centering the body shells and containers relative to the several instrumentalities acting thereon, during passage over the main elevating means, 10 comprises stationary elements lengthwise of said elevating means, opposing relatively-movable grip members in the form of arcual-section elements, and means whereby said grip members are moved towards and away from the stationary elements 15 respectively with the ascent and descent of the elevating means.

23. A machine as defined in claim 16 wherein the guide and grip means for accurately centering the body shells and containers relative to the 20 several instrumentalities acting thereon, during passage over the main elevating means, comprises stationary elements lengthwise of said elevating means, opposing arcual-section grip elements supported by stems slideable in a vertically-movable bearing, links at the free ends of 25 said stems operatively connected to an arm fast on a rock-shaft, said rock-shaft being journaled in spaced bearings of guide brackets projecting laterally from the main elevating means, and 30 means whereby the grip elements are moved inwardly and outwardly respectively as the elevating means is raised and lowered.

24. A machine as defined in claim 16 wherein the guide and grip means for accurately centering the body shells and containers relative to the 35 several instrumentalities acting thereon, during passage over the main elevating means, comprises stationary guide elements lengthwise of said elevating means, opposing arcual-section grip elements supported by stems slideable in a vertically-movable bearing, links at the free ends of 40 said stems operatively connected to an arm fast on a rock-shaft, said rock-shaft being journaled in spaced bearings of guide brackets projecting laterally 45 from the main elevating means, a slotted cam secured to the rock shaft and engaging a freely rotative roller on a stationary lateral projection of the machine framework whereby the arcual grip plates are moved inwardly and outwardly respectively as the main elevating means 50 rises and descends.

25. A machine as defined in claim 16 wherein the means for feeding and sustaining the closure elements, in readiness for insertion into the body 55 shells, comprises a vertically movable head, a tubular magazine for the end closures removably seated on said movable head, a housing on the movable head for the end closure inserting head having a tubular portion in which the stem of 60 said inserting head is axially movable, means normally influencing the movable head downwards, a pendent latch member pivoted to the lower part of the movable head, a cut out at the free end of said latch member for engagement 65 with a stationary bar portion sustained by the main elevator table to effect simultaneous movement of the movable head therewith, a lateral projection on the latch member for engagement by an upward extension of a horizontally movable spring-influenced latch cam fulcrumed intermediate its ends to the main elevator table, and coercive means whereby each successive end closure is moved from the tubular magazine and held in concentric position over the body shell 70 or container below the inserting head.

26. A machine as defined in claim 16 wherein the means for feeding and sustaining the closure elements, in readiness for insertion into the body shells or containers, comprises a vertically movable head, a tubular magazine for the end closures removably seated on said movable head, a housing on the movable head for the end closure inserting head having a tubular portion in which the stem of said inserting head is axially movable, means normally influencing the movable head downwards, a pendent latch member pivoted to the lower part of the movable head, a cut out at the free end of said latch member for engagement with a stationary bar portion sustained by the main elevator table to effect simultaneous movement of the movable head therewith, a lateral projection on the latch member for engagement by an upward extension of a horizontally movable spring-influenced latch cam fulcrumed intermediate its ends to the main elevator table, an ejector device slidably mounted below the vertically movable head and suitably configured for removal of each successive end closure from the lower end of the magazine, opposing links pivoted at one end to the ejector device and at their other ends to the lower extremities of angle levers fulcrumed to the housing tubular portion aforesaid, a freely rotative roller mounted between laterally projecting portions of said angle levers, and an undulate strap-like cam projecting laterally from the applying head stem coercive with said roller to effect operation of the ejector device for removal of each consecutive end closure from the magazine.

27. A machine as defined in claim 16 wherein the means for feeding and sustaining the closure elements, in readiness for insertion into the body shells or containers, comprises a vertically movable head, a tubular magazine for the end closures removably seated on said movable head, a housing on the movable head for the end closure inserting head having a tubular portion in which the stem of said inserting head is axially movable, means in compression normally influencing the movable head downwards, a pendent latch member pivoted to the lower part of the movable head, a cut out at the free end of said latch member for engagement with a stationary bar portion sustained by the main elevator table to effect simultaneous movement of the movable head therewith, a lateral projection on the latch member for engagement by an upward extension of a horizontally movable spring influenced latch cam fulcrumed intermediate its ends to the main elevator table, an ejector device slidably mounted below the vertically movable head suitably and configured for removal of each successive end closure from the lower end of the magazine, opposing links pivoted at one end to the ejector device and at their other ends to the lower extremities of angle levers fulcrumed to the housing tubular portion aforesaid, a freely rotative roller mounted between laterally projecting portions of said angle levers, an undulate strap-like cam projecting laterally from the applying head stem coercive with said roller to effect operation of the ejector device for removal of each consecutive end closure from the magazine, and opposing inwardly-active springs in an annular recess of the lower portion of the vertically movable head between which the transferred end closure is gripped and held against falling until the body shell or container is moved upwards into concentric relation therewith.

28. A machine as defined in claim 16 wherein the marking device comprises paralleling bell-crank members pivoted at each side of the machine, one arm of each of said members being forked for operative coaction with lateral projections on the main elevating means and each other arm is operatively connected to the outer end of a non-rotative stepped-member, guide means for each stepped-member, and means whereby the stepped-members are intermittently reciprocated by ascent and descent of the main elevating means to transfer suitable marking medium from a pad to the active face of the associated stamping device.
29. A machine as defined in claim 16 wherein the marking device comprises paralleling bell-crank members pivoted at each side of the machine, one arm of each of said members being forked for operative coaction with lateral projections on the main elevating means and each other arm is operatively connected to the outer end of a non-rotative stepped-member, a slotted guide for horizontal movement of each stepped-member, each said guide being stationarily carried by the machine, a rod reciprocatively in apertured lugs outstanding from the slotted guide and to which the stepped-member outer end is connected, whereby said stepped-member is intermittently reciprocated by ascent of the main elevating means to effect transfer of marking medium from a pad to the active face of the associated stamping device.
30. A machine as defined in claim 16 wherein the turn-over or inverting mechanism comprises a bracket at the side of the machine, said bracket supporting a bearing element at its upper end, a sleeve on said element having at one end a suitable gear, a slidable sleeve on the first mentioned sleeve and restrained against relative rotation thereto, an abutment roller fixed on the free end of the bearing element, means under compression intermediate the abutment collar and the second mentioned sleeve, opposing radial clamp arms respectively on the abutment collar and slidable sleeve, and means whereby the bearing element is rotated with concurrent inward and outward movement of the clamp arms as the main elevating means ascends and descends respectively.
31. A machine as defined in claim 16 wherein the turn-over or inverting mechanism comprises a bracket at the side of the machine, said bracket supporting a bearing element at its upper end, a sleeve on said element having at one end a suitable gear, a slidable sleeve on the first mentioned sleeve and restrained against relative rotation thereto, an abutment roller fixed on the free end of the bearing element, means under compression intermediate the abutment collar and the second mentioned sleeve, opposing radial clamp arms respectively on the abutment collar and slidable sleeve, a vertically-slotted arm projecting upwardly from the bracket aforesaid and having an inclined cam face engageable by the sleeve gear outer end, and a reciprocative rack cooperative with the sleeve gear to effect actuation of the clamp arms with the ascent and descent of the main elevating means respectively.
32. A machine as defined in claim 16 wherein the turn-over or inverting mechanism comprises a bracket at the side of the machine, said bracket supporting a bearing element at its upper end, a sleeve on said element having at one end a gear, a slidable sleeve on the first mentioned sleeve and restrained against relative rotation thereto, an abutment roller fixed on the free end of the bearing element, means under compression intermediate the abutment collar and the second mentioned sleeve, opposing radial clamp arms respectively on the abutment collar and slidable sleeve, a vertically-slotted arm projecting upwardly from the bracket aforesaid and having an inclined cam face engageable by the sleeve gear outer end, a roller at the angular part of the rock-lever coactive with an eccentric cam on the machine main drive shaft, said rock-lever being pivoted to a stationary fulcrum at one end, and a connecting rod at its other end pivoted to a downward lug below the forward conveyor bar, whereby the turn-over mechanism is intermittently actuated in a clockwise and anti-clockwise direction.
33. A machine as defined in claim 16 wherein the smaller raised means or table is elevated and lowered by the cam operating the conveyor-progressing bars, a shaft below the table having a freely rotative roller projecting sidewise therefrom, and an actuator cam carried by the machine main connecting rod cooperative with the roller aforesaid to effect intermittent ascent and descent of the smaller elevating means or table simultaneously with that of the main elevating table.
34. A machine as defined in claim 16 wherein the vent hole producing means comprises a rigid bracket embodying axially aligned spacedly-separated bored heads, one of said heads housing a peripherally flanged die and an adjustable abutment member, an axially disposed punch in the bore of said die, means normally tending to force the die outwards, a matrix reciprocative in the opposing bored head having a bore for coaction with the punch and an outlet duct connecting with a chute for discharge of the punchings, a slide bar operatively connected at one end to the matrix and having a slotted portion at its other end, a laterally projecting roller at one side of the slotted portion, a tooth cam on a rotary shaft journaled in the machine whereby the slide bar is intermittently moved in the active direction in opposition to automatic return means, and means whereby the rotary shaft is partially turned at regular intervals.
35. A machine as defined in claim 16 wherein the vent hole producing means comprises a rigid bracket embodying axially aligned spacedly-separated bored heads, one of said heads housing a peripherally flanged die and an adjustable abutment member, an axially disposed punch in the bore of said die, means normally tending to force the die outwards, a matrix reciprocative in the opposing bored head having a bore for coaction with the punch and an outlet duct connecting with a chute for discharge of the punchings, a slide bar operatively connected at one end to the matrix and having a slotted portion at its other end, a laterally projecting roller at one side of the slotted portion, a tooth cam on a rotary shaft journaled in the machine whereby the slide bar is intermittently moved in the active direction in opposition to recoil return means, an arm projecting radially from the partially rotative shaft,

- 5 a vertically-reciprocatve bar pivoted to said arm and having an elongate slot for passage of the machine main drive shaft, laterally-projecting freely-rotative rollers in spaced relation to the 5 elongate slot on said bar, and a sectoral cam on said main shaft coacting with said rollers to effect reciprocation of the bar whereby the rotary shaft aforesaid is partially turned at regular intervals to effect the punching operation.
- 10 16. A machine as defined in claim 16 wherein the vent hole producing means comprises a rigid bracket embodying axially aligned spacedly-separated bored heads, one of said heads housing a peripherally flanged die and an adjustable abutment member, an axially disposed punch in the bore of said die, means normally tending to force the die outwards, a matrix reciprocative in the opposing bored head having a bore for coaction with the punch and an outlet duct connecting with a chute for discharge of the punchings, a slide bar operatively connected at one end to the matrix and having a slotted portion at its other end, a laterally projecting roller at one side of the slide bar slotted portion, a tooth cam on a rotary 20 shaft journaled in the machine whereby the slide bar is intermittently moved in the active direction in opposition to a contractile spring, an arm projecting radially from the partially rotative shaft, a vertically-reciprocatve bar pivoted to 25 said arm and having an elongate slot for passage of the machine main drive shaft, laterally-projecting freely-rotative rollers in spaced relation to the elongate slot on said bar, a sectoral cam on the main shaft coacting with said rollers to effect 30 reciprocation of the bar whereby the rotary shaft aforesaid is partially turned at regular intervals to effect the punching operation, in combination with a headed guide stem projecting upwards from the first mentioned bored head, a bridging 35 40 ejector of inverted channel formation on said stem having lateral extensions of a dimension to span the body shell open end, the channel flanges being spaced for coaction with vertical grooves in the bored head, and means reactive between the ejector web portion and the guide stem head effective to force the vented container away from the punching mechanism.
37. A machine as defined in claim 16 wherein the switch for moving each vented empty container, from the forward progressing means to the return progressing means, comprises a vertical pivot having a suitably-contoured transfer arm for effecting lateral movement of the consecutive empty containers, an angularly-related actuator 50 arm whereby the pivot is turnable in one direction, a second arm secured to said pivot with a twist link fulcrumed thereto, said twist link having a suitable connection to the machine connecting rod proximate end with capacity for relative sliding movement, and means whereby the pivot is intermittently turnable in the direction aforesaid by the adjoining progressing means.
38. A machine as defined in claim 16 wherein the switch for moving each vented empty container, from the forward progressing means to the return progressing means, comprises a vertical pivot having a suitably-contoured transfer arm for effecting lateral movement of the consecutive empty containers, an angularly-related 65 actuator arm whereby the pivot is turnable in one direction, a second arm secured to said pivot with a twist link fulcrumed thereto, said twist link having a suitable connection to the machine connecting rod proximate end with capacity for relative 70 sliding movement, a U-shaped end on the proximate

5 mate progressing means, a depending pin on the free limb of said U-shaped end, a sectoral cam on the machine main drive shaft with an associated pivoted arm whereby the progressing means is lowered and moved in one direction to place the 5 depending pin in the path of the actuator arm to swing the transfer arm through the desired angle, an eccentric cam on said main shaft with knee-action links for effecting further movement of the main connecting rod to its limit in the same direction, and means for shifting the connecting rod in the reverse direction to first elevate the U-shaped end with its depending pin above the level of the actuator arm, so that said connecting rod and associated twist link are freed for automatic 10 retraction to normal coactive relation.

39. In a machine as defined in claim 16 wherein the filling mechanism is provided with an outlet control valve of the plug type, an associated measuring-ejector device on said control valve, a 20 relatively eccentric element fixed to the valve plug end, an actuator connection fulcrumed at one end to said element with its remote end having a rectangular aperture, said apertured portion also including a relatively-inclined notch, a slide block 25 operative in the rectangular aperture and pivotally supported by an oscillatory arm fixed to a rotary shaft included in the machine cooperative mechanism, and means whereby the actuator connection is operated. 30

40. In a machine as defined in claim 16 wherein the filling mechanism is provided with an outlet control valve of the plug type, an associated measuring-ejector device on said control valve, a 35 relatively eccentric element fixed to the valve plug end, an actuator connection fulcrumed at one end to said element with its remote end having a rectangular aperture, said apertured portion also including a relatively-inclined notch, a slide block 40 operative in the rectangular aperture and pivotally supported by an oscillatory arm fixed to a rotary shaft included in the machine cooperative mechanism, a second angularly-related arm on said rotary shaft with a vertically-reciprocatve arm pivoted to its free end, said arm 45 having a longitudinal slot therein for passage of the machine main drive shaft, spaced freely-rotative rollers carried by the arm above and below the main shaft, and a sectoral cam on the main shaft coactive with the said rollers to effect timed reciprocal 50 operation of the actuator connection.

41. In a machine as defined in claim 16 wherein the filling mechanism is provided with an outlet control valve of the plug type, an associated measuring-ejector device on said control valve, a 55 relatively eccentric element fixed to the valve plug end, an actuator connection fulcrumed at one end to said element with its remote end having a rectangular aperture, said apertured portion also including a relatively-inclined notch, a slide block 60 operative in the rectangular aperture and pivotally supported by an oscillatory arm fixed to a rotary shaft included in the machine cooperative mechanism, a second angularly-related arm on said rotary shaft with a vertically-reciprocatve arm pivoted to its free end, said arm 65 having a longitudinal slot therein for passage of the machine main drive shaft, spaced freely-rotative rollers carried by the arm above and below the main shaft, a sectoral cam on the main shaft coactive with the rollers to effect timed reciprocal 70 operation of the actuator connection, and means for simultaneously operating the measuring-ejector device.

42. In a machine as defined in claim 16 where- 75

in the filling mechanism is provided with an outlet control valve of the plug type, an associated measuring-ejector device on said control valve, a relatively eccentric element fixed to the valve plug end, an actuator connection fulcrumed at one end to said element with its remote end having a rectangular aperture, said apertured portion also including a relatively-inclined notch, a slide block operative in the rectangular aperture and pivotally supported by an oscillatory arm fixed to a rotary shaft included in the machine cooperative mechanism, a second angularly-related arm on said rotary shaft with a vertically-reciprocative arm pivoted to its free end, said arm having a longitudinal slot therein for passage of the machine main drive shaft, spaced freely-rotative rollers carried by the arm above and below the main shaft, a sectoral cam on the main shaft coactive with the rollers to effect timed reciprocation of the actuator connection, a rack bar extension from the measuring-ejector device, a toothed sector coacting with said rack bar, shaft means sustaining said sector for oscillation in both rotative directions; a link and pitman fulcrumed to a variably-adjustable axis block slidable in an arcual slotted-guide, means for variably adjusting the axis block, an extension at one end of the slotted guide affording pivotal connection for a second pitman, and said second pitman being connected to a crank on the machine main drive shaft to effect operation of the measuring-ejector device simultaneously with opening and closing of the filling plug valve.

43. In a machine as defined in claim 16 wherein in the filling mechanism is provided with an outlet control valve of the plug type, an associated measuring-ejector device on said control valve, a relatively eccentric element fixed to the valve plug end, an actuator connection fulcrumed at one end to said element with its remote end having a rectangular aperture, said apertured portion also including a relatively-inclined notch, a slide block operative in the rectangular aperture and pivotally supported by an oscillatory arm fixed to a rotary shaft included in the machine cooperative mechanism, a second angularly-related arm on said rotary shaft with a vertically-reciprocative arm pivoted to its free end, said arm having a longitudinal slot therein for passage of the machine main drive shaft, spaced freely-rotative rollers carried by the arm above and below the main shaft, a sectoral cam on the main shaft coactive with the rollers to effect timed reciprocation of the actuator connection, a rack bar extension from the measuring-ejector device, a toothed sector coacting with said rack bar, shaft means sustaining said sector for oscillation in both rotative directions, a link and pitman fulcrumed to a variably-adjustable axis block slidable in an arcual slotted-guide, means for variably adjusting the axis block, an extension at one end of the slotted guide affording pivotal connection for a second pitman connected to a crank on the machine main drive shaft, a planarly angled trip-lever pivoted at its angular part on a stationary axis pin, said lever having one end suitably looped for engaging the top edge of each container rising to the filling mechanism control valve, the other end of the trip lever being disposed in the descending plane of the valve actuator and normally spring-influenced upwards in such plane, and a retractile spring normally tending to draw the valve actuator outwards and holding the filler control valve

in closed position, and when a container elevates the looped end of said spring influenced lever the axis block is caused to engage in the actuator slot notch to effect opening of the control valve.

44. A machine as defined in claim 16 wherein the means controlling the degree of heat supplied to the respective container end treating heads comprises an electric motor with a pinion on its extended shaft, speed reducing gears in mesh with said pinion and fixed on the shafts of some of the associated heads, sprockets on said shafts operatively coordinated by suitable drives to speed-reducing sprockets on the other head shafts, and appropriate brushes whereby current is conducted to the respectively associated heating elements.

45. A machine as defined in claim 16 wherein the means for automatically returning the main and auxiliary elevating means to their lowest position comprises a limit switch, an associated on-and-off arm carrying a roller, an upstanding member on a vertically movable bearing of the main elevating means engageable with the upstanding member for intermittently closing-and-opening said limit switch incidental to the rise and fall of the elevating means, but when the latter is approaching its lowermost position, subsequent to interruption of the normal working operation, serving to hold the limit switch open whereby the elevating means is arrested from further elevation and the motive power cut-off.

46. A machine as defined in claim 16 wherein the heater-chamfering heads have associated scraper means, each said means comprising a stationary stud, an inwardly active scraper element pivoted on said stud and having a spring attached between its tail portion and a fixed anchorage, and an inclined cam device carried by the vertically-movable elevating means for engagement with the scraper tail portion incident to descent of a treated body shell or container away from the associated head.

47. A machine as defined in claim 17 wherein each end closure magazine has a vertical slot in its lower portion, an associated detector device, said device being preferably in the form of a counterweight channel-like lever with one arm longer than the other, a relatively offset angularly-directed branch projecting from the lever, said branch when moved into vertical position incident to approaching exhaustion of the end closures, opening an associated mercoid switch in the operative circuit of the machine to give a visible signal of such approaching end closure exhaustion.

48. A machine as defined in claim 17 wherein each end closure magazine has a vertical slot in its lower portion, an associated detector device in the form of a counterweight channel-like lever with one arm longer than the other, a relatively offset angularly-directed branch projecting from said lever, said branch when moved into vertical position, incident to approaching exhaustion of the end closures, opening an associated mercoid switch in the operative circuit of the machine to give visible indication of such approaching end closure exhaustion, and upon full lowering of the main elevating means, in conjunction with the limit switch, jointly effecting full stoppage of the machine.

49. A machine for treating preformed container body-shells comprising, in combination, a shell receiving and progressing mechanism, means for feeding end closure elements to the body shells, an elevating mechanism interposed in the

- path of and coactive with the progressing mechanism, a device for simultaneously heating and chamfering one end of the body shell, additional devices for applying and sealing an end closure 5
5 within an end of a body shell, and mechanism coordinatively actuating all of said devices in timed relation.
50. A machine for treating preformed container body shells comprising, in combination, a shell 10 receiving and progressing mechanism, means for feeding end closure elements to the body shells, a device for simultaneously heating and chamfering one end of the body shell, additional devices for applying and sealing an end closure 15
15 within an end of a body shell, and mechanism coordinatively actuating all of said devices in timed relation.
51. A machine for treating preformed container body shells comprising, in combination, a shell 20 receiving and progressing mechanism, means for feeding end closure elements to the body shells, an elevating mechanism interposed in the path of and coactive with the progressing mechanism, a device for chamfering one end 25
25 of the body shell, and additional devices for applying and sealing an end closure within an end of a body shell, and mechanism coordinatively actuating all of said devices in timed relation.
52. A machine for treating preformed container body shells comprising, in combination, a shell 5 receiving and progressing mechanism, means for feeding end closure elements to the body shells, an elevating mechanism interposed in the path of and coactive with the progressing mechanism, a device for simultaneously heating and chamfering one end of the body shell, and mechanism coordinatively actuating all of said devices in timed relation. 10
53. A machine for treating preformed container body shells comprising, in combination, a shell 15 receiving and progressing mechanism, means for feeding end closure elements to the body shells, an elevating mechanism interposed in the path of and coactive with the progressing mechanism, a device for chambering one end of the body shell, and mechanism coordinatively actuating all of said devices in timed relation. 10
54. A machine for treating preformed container body shells, comprising, in combination, a shell receiving and progressing mechanism, means for feeding and applying end closure elements to the body shells, a device for simultaneously heating and chamfering one end of the body shell, and mechanism coordinatively actuating said devices in timed relation. 20
